UNITED STATES PATENT OFFICE.

ALFRED EDMOND, OF KEARNEY, NEW JERSEY.

FUEL SAVER.

Application filed November 23, 1921. Serial No. 517,306.

To all whom it may concern:

Be it known that I, ALFRED EDMOND, a citizen of the United States, and a resident of Kearney, county of Hudson, and State of 5 New Jersey, have invented certain new and useful Improvements in Fuel Savers, of which the following is a specification.

This invention relates to an improved fuel saver which is of the type that occupies 10 a material amount of space in the center of the fire box so as to cause the combustion of coal to take place close to the walls of the fire box.

The invention is designed to provide a 15 casing or dome of a construction that will permit it to be placed in any heater through the fire door and, when assembled, to form a firm substantial support over which a cover or cap of fire brick or other refractory 20 material is placed, the latter being also insertable through the fire door as it is made in sections.

The invention is illustrated in the accompanying drawing, in which Figure 1 is an 25 elevation of a device embodying my invention, being shown in a fire box of a heater, a portion of which is shown in section. Figure 2 is a horizontal sectional view, 30 broken away at parts to more clearly illustrate the invention. Figure 3 is a sectional perspective of the device shown in Figure 1. Figure 4 is a detail perspective of the bottom part of the casing of the device. Figure 5 shows one form of supporting fixture 35 in partial perspective, and Figure 6 is another detail perspective view of the inner casing or dome of the device.

In the drawing 10 illustrates the fire box 40 of an ordinary heater, the outer walls 11 of which extend down to approximately the level of the grate 12 and thus form water chambers 13, to which chambers it is desirable to apply the heat of the fire to secure the best results. Therefore it is necessary 45 to occupy a portion, preferably the central portion, of the fire box with a casing or dome which will, in conjunction with the walls 11, form an anular receptacle for coal, thus effecting a material saving in the 50 amount of coal used, since the fire box will not hold so much coal as before the device was installed, but providing as much or more heat to the water in the furnace.

The dome or casing consists of an inner 55 casing or dome 14 which is made to substantially conform to the shape of the fire box,

and since a round fire box is shown I illustrate a round dome which is made up of more than one member, the form shown comprising two members 15 and 16 which 60 are placed together side by side, forming a vertical joint between them, which joint is tightly closed by suitable means, such as the screws 17 which are accessible through the slots or openings 18 in the members and 65 which have horizontal partitions 19 near the bottom to keep out air and prevent undue cooling of the device, as will be evident hereinafter.

The bottoms of the members are prefer- 70 ably provided with a flange 20 which extends outwardly therefrom and forms a convenient element on which the fire brick or other refractory covering of the dome 14 is supported. The refractory covering or 75 shell is made in more than one piece, the preferred form being a member or ring 21 which is slipped over the assembled members 15 and 16 and rests on the flange 20 of each member. A cap 22 fits over the top 80 part of the dome 14 and rests thereon, the top part of the dome and the top part of the cap 22 being usually formed with a slight and similar curvature so as to shed coal toward the sides when the grate is 85 shaken and to also support the cap 22 for substantially its entire top surface.

The device is installed in the fire box so 90 that it does not interfere with the rotation of the grate bars 12, and in the form shown such support consists of T-irons 23 and 24 which extend at right angles to the fire box 95 above the grate and are fastened to suitable lugs 25 usually present in fire boxes at the corner of the grate, these bars being ar- 100 ranged diagonally and one of them, as 24, being cut away, as will be seen from Figure 4, to permit the passage of the other, and being preferably cut away far enough back so that the rib thereon forms a shoulder, as shown at 26 in Figure 3, against which the flange 20 rests. The device can set down over this bar, since the other bar is permitted to pass through the casing, since it is cut away, as at 27 in Figures 2 and 4, to receive 105 the bar 23.

The supporting means as described above 110 can be changed, however, to meet conditions in different forms of furnaces, so long as the supporting means in the dome is cut high enough above the grate to permit the grate bars to be rocked.

I claim:

1. A fuel saver comprising a casing formed of two members adapted to be secured side by side, a covering of refractory material, said covering comprising a lower member to surround the bottom part of the casing and an upper part to surround the upper sides and the top of the casing.
2. A fuel saver comprising a hollow casing made of two members to be assembled side by side, the members having horizontal partitions near the bottom to form a closed bottom when the members are assembled, means for detachably securing the members together, and a covering of refractory material comprising a bottom member to encircle the lower part of the casing and an upper member in the form of a cap to rest

on the lower member and enclose the upper part and the top of the casing.

3. A fuel saver comprising a casing having a closed bottom and a rounded top and formed of two members adapted to be detachably secured together, the casing having a flange at the bottom thereof, a covering of refractory material comprising a lower member to encircle the lower part of the casing and rest on the flange and an upper member in the form of a cap to cover the upper part of the casing and rest on the lower member.

In testimony that I claim the foregoing, I have hereto set my hand, this 18th day of November, 1921.

ALFRED EDMOND.
